UNITED STATES PATENT OFFICE.

GEORGE H. STRIKER, OF BUFFALO, NEW YORK.

SPECTACLE-CASE.

SPECIFICATION forming part of Letters Patent No. 326,065, dated September 8, 1885.

Application filed November 26, 1884. (No model.)

To all whom it may concern:

Be it known that I, GEORGE H. STRIKER, of the city of Buffalo, in the county of Erie and State of New York, have invented a new and useful Improvement in Spectacle-Cases, of which the following is a specification.

This invention relates to an improvement in spectacle-cases which are provided with a clasp or locking device, whereby they can be firmly fastened in the pocket and prevented from being lost.

My invention consists of the improvement in the construction of the locking device, which will be hereinafter fully set forth, and pointed out in the claim.

In the accompanying drawings, Figure 1 represents a side elevation, and Fig. 2 a front elevation, of a spectacle-case provided with my improvement. Fig. 3 is a vertical longitudinal section of the case. Fig. 4 is a cross-section in line x x , Fig. 2. Fig. 5 is a perspective view of the plate whereby the clasp is secured to the case.

Like letters of reference refer to like parts in the several figures.

A represents an ordinary spectacle-case, constructed of any suitable material and of the usual flattened tubular form, open at the top and closed at the bottom.

B represents my improved clasp applied to the outer side of the case A. The clasp B consists of a plate or bar, b , secured near its upper end to the front side of the case, and bearing with its lower bent end against the case. The bar b is secured to the case A by means of a plate, C, which is provided on its under side with prongs or teeth d , which latter are inserted through openings formed in the front side of the case, and bent or clinched on the inner side of the case, as clearly shown in Fig. 4.

e e are lugs or ears projecting from the sides of the plate C, and f f are similar lugs formed on the bar b . The bar b is pivoted to the plate C by a pin, g , which is inserted through the lugs e and f .

h represents a flat spring, which is inter-

posed between the bar b and the plate C. The ends of the plate C are turned up or bent over, forming hooks i i , which receive the ends of the spring h . The spring is held in place by means of the turned-up ends i and lugs e of the plate C.

k represents a lug extending downwardly from the bar b and bearing against the spring h , whereby the lower bent end of the bar b is held against the case. The lug k is formed by a U-shaped slot cut in the bar b and turning down the metal within the slot, as shown in Figs. 2 and 3.

When the case A is placed in the pocket, the upper end of the bar b is depressed sufficiently to permit the lower bent end of the bar to be inserted over the outer side of the pocket, and by releasing the upper end of the bar the spring h will cause the lower bent end of the bar to bear against the outer side of the pocket, thereby clamping the outer portion of the pocket firmly against the case and preventing the latter from dropping out of the pocket. The lower edge of the bar is preferably serrated or sharpened, so as to take a firm hold upon the cloth.

My improved clasp can be cheaply constructed and secured to the case at comparatively small expense, and forms a reliable fastening, whereby the case is firmly held in place in the pocket.

I claim as my invention—

The combination, with a spectacle-case, of the plate C, secured to the case and provided with lugs e e and turned-up ends i i , a bar, b , pivoted to the lugs e e and provided with a lug, k , and a spring, h , confined between the ends i i of the plate and bearing against the lug k , whereby the lower end of the bar b is held against the case, substantially as set forth.

Witness my hand this 11th day of October, 1884.

GEO. H. STRIKER.
